United States Patent Office.

JOHN HEUERMANN, OF DAVENPORT, IOWA.

Letters Patent No. 94,741, dated September 14, 1869.

IMPROVED TUMBLING-ROD COVER.

The Schedule referred to in these Letters Patent and making part of the same.

Be it known that I, JOHN HEUERMANN, of Davenport, in the county of Scott, and State of Iowa, have invented a new and improved Tumbling-Rod Cover; and I do hereby declare that the following is a true and exact description thereof.

The nature of my invention consists in the construction of a tumbling-rod cover, by using half-wheels or flanges of wood or other material, to which half-wheels or flanges I attach covers of metal, which rest securely over each coupling, while such half-wheels are connected (between the coupling joints from end to end of each rod) by a tubing or cover of canvas, leather, or other material, to which are attached, on inside, small half-wheels or supports to tubing or cover for rods, through which half-wheels the tumbling-rod revolves.

For more particular description I refer to accompanying drawings, in which—

Figure 1 is a perspective view.

Figure 2, a view of inside of tumbling-rod cover.

Figure 3, a view of centre double half-wheels, to which are attached supports or feet.

Figure 4, a view of small half-wheels used inside of canvas tubing or cover.

Figure 5, the end half-wheels, to which is attached, as represented, the iron plate from which chains are passed to separator and power, for tightening the tubing or cover.

Letter A represents the metal covers, which are fastened securely over the couplings to the large half-wheels or flanges.

Letter B represents the notch in large half-wheels, to admit of their opening, so as to pass over tumbling-rod.

Letter C represents the strap or cord by which tubing or cover is held firmly together.

Letter D represents the chains by which the tubing or cover is drawn up tight, and the metal covers held securely to their places.

What I claim for my invention, and desire to secure by Letters Patent, is—

The arrangement and combination of tumbling-rod cover, as shown on drawings, and described in specifications.

JOHN HEUERMANN.
